UNITED STATES PATENT OFFICE.

ALFRED J. MEDLAR, OF PHILADELPHIA, PENNSYLVANIA, ASSIGNOR TO A. J. MEDLAR COMPANY, (LIMITED,) OF SAME PLACE.

DESIGN FOR A CRACKER OR BISCUIT.

SPECIFICATION forming part of Design No. 13,909, dated May 15, 1883.

Application filed April 19, 1883. Term of patent 3½ years.

To all whom it may concern:

Be it known that I, ALFRED J. MEDLAR, a citizen of the United States, and a resident of Philadelphia, Pennsylvania, have invented or produced a new and useful Design for a Biscuit or Cracker, of which the following is a specification.

My design for a biscuit or cracker is fully represented by the figure in the accompanying drawing, and it consists of the representation of one of the shells of a clam, as shown.

I claim—

The design for a biscuit or cracker, consisting of the representation of a shell of a clam, substantially as shown and described. 15

In testimony whereof I have signed my name to this specification in the presence of two subscribing witnesses.

A. J. MEDLAR.
